TUBE ELEMENT SUPPORT

Application filed January 17, 1928. Serial No. 247,302.

This invention relates to vacuum tubes and particularly to a means for supporting the elements of a vacuum tube.

In the ordinary construction of a vacuum tube, several supporting conductors are heated in a glass press within the tube, one of which conductors forms a means to support the upper ends of the elements of the tube in spaced relation to each other, while the lower ends of the elements are supported from the conductors adjacent the press. This construction gives rise to certain disadvantages in the tube, one of which is that any displacement of the elements with respect to their original alignment in the tube caused by a sudden jar, for instance, will cause a variation of the spacing between the elements due to the fact that the various supports are of different lengths and not in the same plane.

It is one of the objects of the present invention, therefore, to provide a means to support the elements of a vacuum tube so that displacements of the elements caused by sudden jars incidental to shipping and handling will not displace the elements with respect to each other.

Another object of the invention is to provide a means for supporting the elements of a vacuum tube which is inexpensive and forms a construction easy to assemble with a minimum of operations.

Other objects and objects especially relating to economies of construction will be apparent as the description of the invention proceeds.

One embodiment of the invention has been illustrated in the accompanying drawing, in which

Fig. 1 is an elevation partly in section of a vacuum tube embodying our invention;

Fig. 2 is a vertical section of the tube shown in Fig. 1 and taken substantially on the line 2-2 of Fig. 1;

Fig. 3 is a horizontal section of the tube taken substantially on the line 3-3 of Fig. 1; and

Fig. 4 is a perspective view of one of the insulating spacers used to support the elements.

Referring now more particularly to the drawing, the invention is shown in connection with a four element vacuum tube 10, having a glass envelope 11 and a base 12 at the bottom of which are mounted the terminals 13 for making the necessary connections to the circuit with which the tube is used. A press 14 is provided within the envelope 11 and forms the means to support the various conductors which are sealed 55 therein. A conductor 15 is sealed in one side of the press and extends upwardly within the tube to a point adjacent the upper end thereof. This conductor forms the support for the plate 16 which is formed of 60 a tubular shell having flanges 17 and 18 for welding together. The flange 18, however, is extended beyond the flange 17 and grooved to receive the conductor 15 to which it may be spot welded to rigidly connect the plate 65 with the conductor 15. A tubular cathode 19 extends concentrically within the plate 16 and is somewhat longer than the plate so that its ends extend beyond the ends of the plate. The cathode 19 may be supported at 70 its upper end by a band 20 which passes around the end of the cathode and is welded thereto and at its lower end by a band 21 which is also welded to the end of the cathode around which it passes. Both the bands 75 20 and 21 extend outwardly substantially parallel with the plane of the press and are welded to a support 22 which is parallel to the support 15 and is sealed into the press 14 at the opposite side thereof. A filament 80 23 is provided for heating the cathode 19 and this filament is attached at its lower end to the support 24 which is sealed in the press 14 at its upper end by a spring 25 which is 85 in turn welded to the upper end of the support 22. The spring 25 is under tension so that the filament is always maintained straight and taut. A grid comprising a coil 90 of wire 26 is provided around the cathode 19 and the adjacent turns of the coil are welded to a support 27 on one side and a support 28 on the other which latter support 95 is preferably extended down to the press 14 into which it is sealed.

As far as the above description goes, the 100

elements of the tube are supported in spaced relation, but in case of sudden jars, there is nothing to prevent any one of the elements from moving with respect to the others so that the cathode for instance, might be caused to touch the grid or the filament to touch the cathode, but this possible displacement of the elements is prevented by means of insulating spacers preferably formed of mica which cooperate with the elements in the following manner: A pair of spacers 29 are provided, one at the upper end and one at the lower end of the elements. Each has a hole 30 into which the cathode may easily fit, and holes 31, 32, 33 and 34 to receive the conductors 15, 27, 28 and 22 respectively. The insulating spacers 29 may be placed adjacent the upper and lower ends of the plate and may be held in place by slightly bending the ends of the conductors as at 35 or 36, one such bend being sufficient above and below the spacers 29 to hold the same in place.

The strip 21 which is attached to the lower end of the cathode is preferably attached tangent to one side thereof as indicated in Fig. 3, so that this strip will clear the conductor 28, from which it must be kept electrically separated.

In order to space the lower end of the filament 23 from the cathode 19 we provide a quartz sleeve 30' which may be placed around the conductor 24 and extend from the press to a point up inside the cathode thereby effectively spacing the filament from the cathode and preventing a possible strain on the filament.

With the construction shown above, a sudden jar on one side of the tube might cause all of the supports 15, 24, 28 and 22 to bend at a point adjacent the press 14, but all the elements are spaced from each other at the top and bottom by the mica and quartz spacers and hence, all would move together so that there would be no danger of any two of the elements touching each other.

While we have shown the invention as applied to a heater type tube, it is evident that it will be equally as effective applied to a tube having a filamentary cathode, and although we have shown and described one embodiment of the invention, we do not desire to limit ourselves to this specific construction, but to interpret the invention broadly within the scope of the appended claims.

Having thus described our invention what we claim is:

1. In a vacuum tube, a plurality of elements, an insulating plate cooperating with the lower ends of said elements to hold the same in spaced relation from each other, an insulating plate cooperating with the upper ends of said elements to hold said elements in spaced relation from each other, a heating filament extending above said upper insulat-

ing plate and below said lower insulating plate, and means to space said filament from said other elements at the lower end thereof.

2. In a vacuum tube, a tubular anode, a grid, a tubular cathode, a support for said anode extending above and below the same, a support for said grid, also extending above and below the same, a pair of mica plates having holes therein corresponding in size to said supports and said cathode, one of said plates being positioned adjacent the top of the anode with said supports and said cathode extending through the openings therein, said other plate being positioned against the bottom of said anode, said supports and said cathode extending through the openings therein, and the upper and lower ends of at least one of said supports being bent at a slight angle to hold the plates in position.

3. In a vacuum tube having a plurality of elements, one of which is a filament, an insulating sleeve adapted to space the lower end of said filament from the element adjacent to it, said sleeve having a shoulder cooperating with said element to maintain said sleeve at the lower end of said filament against upward longitudinal motion, and an insulating plate adapted to space the lower ends of the other elements from each other.

4. In a vacuum tube, a plurality of elements including a filament, an insulating sleeve adapted to space the lower end of said filament from the element adjacent to it, said sleeve having a shoulder cooperating with said element to maintain said sleeve at the lower end of said filament against upward longitudinal motion, an insulating plate adapted to space the lower ends of said other elements and an insulating plate adapted to space the upper ends of said other elements.

5. In a vacuum tube, a tubular cathode, a heater filament for said cathode and separated therefrom by vacuous space and a quartz sleeve between the lower end of said filament and said cathode, said sleeve resting on the press and said sleeve having a shoulder in engagement with the end of the cathode to prevent upward longitudinal movement of the sleeve.

In testimony whereof, we affix our signatures.

CLARENCE A. HORN.
ROBERT J. HEITZMAN.
